UNITED STATES PATENT OFFICE.

WILLIAM T. BAILEY, OF ELMIRA, NEW YORK, ASSIGNOR TO THE CARTER CRUME COMPANY, LIMITED, OF TORONTO, CANADA, A CORPORATION OF CANADA.

PAPER-DELIVERY MECHANISM.

No. 908,832.

Specification of Letters Patent.

Patented Jan. 5, 1909.

Application filed October 21, 1903, Serial No. 177,852. Renewed May 4, 1905. Serial No. 258,892.

To all whom it may concern:

Be it known that I, WILLIAM T. BAILEY, a citizen of the United States of America, and a resident of Elmira, Chemung county, New York, have invented certain new and useful Improvements in Paper-Delivery Mechanism, of which the following is a specification.

This invention relates to means for handling material in sheet form, more specifically, to means for receiving and delivering sheets of paper as from a printing press.

One of the objects thereof is to provide simple and efficient means for receiving sheets of material and transmitting the same to the desired destination.

Another object is to provide practical means of the above type for accumulating the desired number of sheets in even and uniform piles before transmission.

Other objects will be in part obvious and in part pointed out hereafter.

The invention accordingly consists in the features of construction, combinations of elements and arrangement of parts which will be exemplified in the mechanism hereinafter described and the scope of the application of which will be indicated in the following claims.

The accompanying drawing, wherein is shown one of various possible embodiments of my invention, is a perspective view of the same.

As conducing to a better understanding of certain features of my invention, it may here be noted that in mechanism of the general type with which this invention deals, it is of importance that the sheets be accumulated in an even pile so as to facilitate removing, packing and storing the same and also to render them easily counted by hand if desired. If the sheets be thrown by a fly or equivalent element against inaccurately positioned or loose guides, the resulting pile is uneven and irregular. The above and other defects are obviated in constructions of the nature of that hereinafter described.

Referring now to the accompanying drawings there is shown a frame 1 having mounted thereon, as by means of a rock shaft 2 a fly 3 of a well-known type and adapted to perform its usual functions. This fly is preferably actuated through an arm 4 fixed upon the rock shaft and having its free end connected by link 5 with a lever arm 6 provided with a roller 7 adapted to co-act with a cam

8 mounted upon the frame of the machine. The sheets of material, as printed papers, when this mechanism is used in connection with a printing press for which use it is peculiarly adapted, are transmitted through a sheet path 9, actuated in any desired manner, so as to be brought thereby opposite the operative portions of the fly 3.

Mounted upon the frame 1 is a pulley 10 over which passes a belt 11 traveling over a co-acting pulley 12 which is likewise mounted upon the frame of the machine. It may here be noted that by the term "belt", as used throughout this specification and in the following claims, is intended any flexible member adapted to perform the desired functions whether the same be in the form of chains, tapes, a plurality of narrow belts or otherwise. Fly 3 is adapted to deliver the sheets, as 13, upon the belt 11, the same being guided into the desired position by means of fixed guides which will be herein-after described in detail. The guides 14 are preferably mounted upon the frame of the machine and act upon the lower edges of the sheets so as to direct the same into a position in which each sheet is exactly superimposed upon that below the same. Guides 15 are secured upon a cross-bar 16 to ends of which are fixed arms 17 and 18 terminating upon a rock shaft 19. Likewise fixed upon the latter member as by means of the perforated lug 20 and set screw 21 is a lever 22.

Mounted upon the frame 1 is a gear 23 driven in any desired manner as through the pinion 24 and having fixed thereon a pin 25 adapted at each revolution of the gear to engage and raise the lever 22, thus rocking shaft 19 and raising the rods of arms 17 with the parts associated therewith. Also fixed upon gear 23 is a projection 26 adapted to engage and swing an abutment 27 mounted upon a sleeve 28 which is journaled upon a stud 29 formed upon the frame of the machine. Sleeve 28 is provided with a crank arm 30 normally held in its uppermost position by means of a spring 31 coiled about a rod 32 pivotally mounted upon the frame of the machine. This spring engages a lug 33 formed upon the arm 30 and at its lower end takes against an adjustable collar 34, thus tending to throw the arm upwardly or away from the pivot of the rod. The free end of crank arm 30 is connected as by a link 35 with an arm 36 loosely mounted upon the

shaft 37 of the pulley 10. A pawl 38 upon the opposite end of arm engages a ratchet 39 fixed upon a shaft 37 and is adapted as the abutment 27 is engaged and swung by 5 the projection 26 to cause a movement of the belt 11 in the direction indicated by the arrow upon the drawing.

The operation of the above described embodiment of my invention is substantially as 10 follows: Assuming that sheets 13 are brought through the sheet paths 9 to a position opposite the fly 3, the entire machine is so adjusted and synchronized as to throw each sheet downward by means of the fly immediately upon its arrival against the guiding members 14. In this manner the desired 15 number of sheets is thrown upon belt 11, the same being accurately guided and positioned by means of the stationary guides 14 and the 20 movable guides 15. As these guides are rigidly held in the desired place and when in operative condition always assume exactly 25 the same position with relation to the remaining elements of the machine, a smooth and uniform pile as at 40 is guaranteed. After the deposit of a predetermined number 30 of sheets upon the belt 11, the gear 23 is brought to a position in which the pin 25 engages and throws upwardly the lever 22, 35 thus raising the guides 15. As these guides are raised the projection 26 engages abutment 27 and rocks the same about the stud 29 so as to move the belt throughout a predetermined distance by means of a mechanism 40 above described. In this manner the accurately positioned pile of sheets is drawn without distortion from the stationary guides 14 into a position as at 41, in which case they may be readily removed and any desired 45 position made thereof. The mechanism is so adjusted as immediately upon the lateral removal of each pile of sheets to release the lever 22 and permit the guides 15 again to fall into operative position and receive the next succeeding sheet delivered by the fly 3. In this manner the operation of the machine is continuous and each pile is delivered in the desired form.

It will thus be seen that I have provided 50 mechanism well adapted to accomplish the several objects of my invention and that this mechanism is not only of simple and inexpensive construction but the action of the several parts is so positive and reliable as 55 practically to do away with any necessity for supervision other than the removal of each pile of sheets as it is delivered into the desired position. The mechanism, moreover, while capable of attaining a high speed 60 is so simple and direct in action as to do away with chance of injury to the sheets.

As many changes could be made in the 65 above construction and many apparently widely different embodiments of my invention could be made without departing from

the scope thereof, I intend that all matter contained in the above description or shown in the accompanying drawings shall be interpreted as illustrative and not in a limiting sense.

70

I desire it also to be understood that the language used in the following claims is intended to cover all of the generic and specific features of the invention, which as a matter of language, might be said to fall therebetween.

75

Having described my invention, what I claim as new and desire to secure by Letters Patent, is:—

1. In a machine of the class described, in 80 combination, a belt, a relatively fixed guide projecting above said belt, a fly adapted to coact with said guide in depositing a predetermined number of sheets in superposed relation to form a pile upon said belt, and 85 means adapted upon said predetermined number of sheets being deposited to move said belt to carry the pile away from said guide and said fly and permit the same to form another pile.

90

2. In a machine of the class described, in combination, a belt, a relatively fixed guide projecting above said belt, a fly adapted to coact with said guide in depositing a predetermined number of sheets in superposed relation to form a pile upon said belt, and 95 means adapted upon said predetermined number of sheets being deposited to move said belt to carry the pile away from said guide and said fly and permit the same to 100 form another pile, said guide being formed and mounted to curve toward the axis of said fly.

95

3. In a machine of the class described, in combination, a sheet receptacle comprising 105 guiding means and means upon which the sheets rest, and means adapted to withdraw said guiding means and shift said second means.

4. In a machine of the class described, in 110 combination, a sheet receptacle comprising guiding means and means upon which the sheets rest, and means adapted to withdraw said guiding means and shift said second means laterally immediately upon said guiding means being withdrawn.

115

5. In a machine of the class described, in combination, a sheet receptacle comprising guiding means and means upon which the sheets rest, means adapted to deposit a sheet 120 within said receptacle, and means adapted to withdraw said guiding means and shift said second means laterally immediately upon said guiding means being withdrawn.

120

6. In a machine of the class described, in 125 combination, a sheet receptacle comprising guiding means and means upon which the sheets rest, means adapted to deposit a plurality of sheets singly within said receptacle, and means adapted upon a predetermined 130

number of sheets being deposited to withdraw said guiding means and shift laterally said second means.

7. In a machine of the class described, in combination, a sheet receptacle comprising guiding means and a belt upon which the sheets rest, means adapted to deposit a plurality of sheets singly within said receptacle, and means adapted upon a predetermined 10 number of sheets being deposited to withdraw said guiding means and move said belt throughout a predetermined distance.

8. In a machine of the class described, in combination, a sheet receptacle comprising 15 stationary guiding means, movable guiding means, and means upon which the sheets rest, means adapted to deposit a plurality of sheets singly within said receptacle, and means adapted upon a predetermined number 20 of sheets being deposited to raise said movable guiding means and shift said third means laterally.

9. In a machine of the class described, in combination, a sheet receptacle comprising 25 stationary guiding means, movable guiding means, and a belt upon which the sheets rest, means adapted to deposit sheets within said receptacle, and means adapted to withdraw said movable guiding means and shift 30 said belt throughout a predetermined distance away from said stationary guiding means.

10. In a machine of the class described, in combination, a sheet receptacle comprising 35 stationary guiding means, movable guiding means and a belt upon which the sheets rest,

means adapted to deliver a plurality of sheets singly within said receptacle, and means adapted upon a predetermined number of sheets being delivered to raise said movable 40 guiding means and shift said belt laterally throughout a predetermined distance in a direction away from said stationary guides immediately upon said movable guiding means being raised. 45

11. In a machine of the class described, in combination, a belt, a fly adapted to deliver sheets thereon, a fixed guide adapted to direct said sheets into the desired position upon said belt, a movable guide adapted to engage 50 the opposite edges of said sheets, and means adapted upon said fly delivering a predetermined number of sheets upon said belt to raise said movable guide, draw said sheets away from said fixed guide and permit said 55 movable guide to fall into operative position.

12. In a machine of the class described, in combination, a belt, a pulley adapted to drive said belt, a ratchet operatively connected with said pulley, a fly adapted to deliver sheets upon said belt, guiding means adapted to position said sheets upon said belt, and means adapted to withdraw said 60 guiding means and actuate said pulley through said ratchet. 65

Signed at New York city this 26th day of September 1903.
